Application August 15, 1932, Serial No. 628,932

14 Claims.

(Cl. 32—8)

The invention relates to the art of manufacturing artificial teeth and has for its object first, the obtaining of a construction of mechanical teeth superior to teeth of anatomical form; second, to obtain a method of generating the basic form of such teeth; third, to so modify this basic form as to have more of the appearance of anatomical teeth and to also improve the functioning thereof.

With these general and other more specific objects in view the invention consists in the construction and method as hereinafter set forth.

In the drawings:

Figure 1 is a geometrical design showing the occlusal construction of our primary forms on the lower jaw from the transverse aspect;

Figure 2 is a diagram illustrating the method of adapting an articulator to the process of cutting the occlusal surfaces of the primary tooth forms shown in Figure 1;

Figures 3 and 4 are respectively front and side views of one of the cutting tools;

Figures 5 and 7 are plan views illustrating the occlusal view respectively of the upper and lower right bicuspids and molars;

Figure 6 shows the right side elevation of the upper and lower units in engagement, the upper being one half cusp posterior to the lower;

Figure 8 shows a transverse sectional vertical view of the teeth after they have been placed in dentures;

Figure 9 shows a transverse vertical sectional view of one upper and one lower molar illustrating a system of cusp plane relief;

Figure 10 is a perspective view of the lower second molar tooth illustrating both positive and negative trihedral planes and the balancing plane;

Figure 11 shows one of the finished tooth models embodying hand carved features simulating natural teeth without destroying the primary masticating surfaces and from which corresponding porcelain teeth may be made.

In normal human jaws there are thirty-two teeth, of which, twenty are bicuspids and molars.

In artificial teeth experience has shown that only sixteen bicuspids and molars are either desirable or necessary. These are divided into four operating units, one on each side of the upper, as well as the lower jaw; each unit consisting of two bicuspids and two molars.

The human mandible makes, in addition to the opening and closing movements, right and left lateral movements, protrusive (forward),

retrusive (backward) and any combination of these movements.

Anatomists have shown that the human mandible moves in certain definite paths. In protrusive movement, the head of the condyle moves forward and downward, the path taken being determined by the anterior wall of its socket, or glenoid fossa. The angle between the slope of this wall (XX' Fig. 2) and the horizontal plane of occlusion (HH' Fig. 2) is the protrusive angle. 10 Protrusive angles vary in all individuals, even in the same individual, ranging from 0 degrees to 60 degrees, however, our records show that eighty-five percent come between 25 and 35 degrees, and further that ninety-four percent come 15 between 20 and 40 degrees. This indicates that 30 degrees is the center or average of ninety-four percent of human jaw actions from the protrusive standpoint, therefore we have allowed this to be the deciding factor in determining the vertical 20 aspect of our tooth surfaces.

The lateral movement of the condyle head influences the design of the occlusal or biting surfaces of artificial teeth. In this movement, known as the Bennett movement, the head of the 25 condyle moves bodily sidewise during side bites in a direction determined by the posterior wall of the glenoid fossa. The angle of the paths of this horizontal movement is taken from the sagittal plane, (SS' Fig. 1) and varies from 5 degrees 30 to 25 degrees in human jaws.

Another movement of importance in the design of the occlusal surfaces of teeth is the so-called Gothic arch movement. This movement is carried out in practice by the incisal guide pins on 35 adaptable articulators, and is determined in the human jaws by placing a pencil-tracer at a point corresponding to (I Fig. 1), between the central incisors of one jaw, and, making right and left lateral movements, thus recording on a card 40 firmly attached to the other jaw an obtuse angle (Gothic arch angle) which varies in human jaws from 100 to 130 degrees, and which represents the combined right and left movements. If a line (SS' Fig. 1) be dropped back from (I) to point 45 (00) parallel to the sagittal plane, the composite angle will be divided into its right and left component angles, which vary from 50 to 65 degrees each.

If on both bows of any good adaptable articulator, blocks of plaster (with carborundum powder incorporated) are fastened, the condyle inclinations set at 30 degrees, the incisal guide pin removed, and all masticating movements made with the articulator, thereby grinding the blocks 55

so that they will be in perfect approximation throughout any and all movements of the articulator, the resultant surfaces become perfect arcs of spheres, the upper being convex, and the lower concave, and each arc the segment of a 12% inch sphere.

If the incisal guide pin is replaced, the incisal guide plane set at 30 degrees, and the lower block protruded, the blocks will separate progressively as the lower is pushed forward, and the opening varies as mandibular movements are made, showing that masticating movements do not take place in a horizontal plane, but actually take place in a plane more or less parallel to the condyle inclinations.

For this reason, all posterior teeth have to be provided with ridges or cusps having plane angles harmonizing with condyle inclinations as shown by the inclined cusp angles in Figure 2, and further, must be designed so that the crests of the cusps follow the antero-posterior curve (compensating curve CC' Fig. 2) of the blocks, to compensate for the opening component in protrusive movement.

Artificial teeth thus far invented have either been copies of natural teeth (anatomical teeth) or have been radical departures (mechanical teeth). The anatomical teeth do not function because the cusp planes do not harmonize with either the cusp planes of adjacent teeth or opposing teeth, thereby causing cusp interference or locking during jaw movements. In mechanical teeth cusp interference has largely been eliminated by eliminating cusps, thereby encountering difficulty in protrusive bites through lack of balancing cusp planes. Until now no attempt has been made to combine the two principles and produce anatomical-mechanical teeth in which the two characteristics are combined to a common maximum.

The perfect set of artificial teeth requires:

1. Teeth designed having average protrusive jaw movements, thus requiring a minimum of cusp change to fit higher or lower angles;

2. Teeth in which all primary cusp planes run parallel to corresponding planes in the opposing teeth, thus preventing intercusp interference during jaw movements;

3. Teeth in which all primary cusp planes during their movements harmonize, not only with opposing planes, but also with the angles (Bennett and Gothic arch) at which the human jaw moves in a lateral relation;

4. Teeth in which the transverse angles of the primary cusp planes are practically equal to the composite maximum Bennett and Gothic arch angles, thereby creating function within greater limits than the limits found in a large majority of human jaw movements;

5. Teeth in which ample grooves or gateways are provided for all opposing cusps, thereby permitting full freedom for cusp movement during mastication;

6. Teeth in which all intermediate masticating movements are free from restraint, sliding from one position to another without interference;

7. Teeth in which the tooth opening angles (angle 3H-2A-13A Fig. 9) are such that the dentures in which the teeth are set are held firmly against the ridges at all times by the forces exerted by mastication;

8. Teeth, the primary forms of which require a minimum of hand carving to create superior anatomical characteristics without altering the primary character of the cusp planes;

9. Teeth in which the method of cutting the primary forms may be adapted to produce intercusp clearance which allows a range in angles in protrusive, lateral, and balancing movements, and which will create clearance in intercusp movement, freedom in centric relation and provide a working latitude to compensate for discrepancies in the finished dentures due to unskilled labor or changes incurred during the vulcanization process.

Any method of designing artificial sets of teeth must be capable of designing them not only as upper and lower units of eight teeth, functioning in harmony with jaw movements as the two halves of a cutting and grinding machine, but must further be flexible enough to permit any tooth to be designed independently for any specialized purpose, or to permit the change in size and position of any tooth, or the position or angle of any cusp or series of cusps without altering the remainder of the tooth or teeth in the set.

The object of the present invention is to provide such a method to produce primary forms of the sixteen posterior teeth which can be used as models in the manufacture of artificial denture teeth. The primary forms are made of plaster or artificial stone and represent the upper right and left first bicuspids, second bicuspids, first molars and second molars, and the lower right and left first bicuspids, second bicuspids, first molars, and second molars.

A further object is to provide these forms of teeth with biting surfaces made up of cusps which in principle, design and action include and embody the above mentioned requisites of a perfect denture.

Referring more specifically to Figure 1, points M and Q correspond to the natural position of the temporo-mandibular joint, also represented by point M in Figure 2. The point I represents the incisal point, and the angle GIG' represents the combined right and left Gothic arch angles. The lines X'X' and XX represent the lateral paths of the condyles during side movements (each being 20 degrees from the sagittal plane). The points RC and RC are the rotation centers which are in the articulator behind and outside the condyles and which are geometrically determined by dropping perpendiculars from the incisal point junction I of the right and left Gothic arch angles GI and G'I and extending them to intersect lines from the condyle points M and Q and perpendicular to the lines XX and X'X' which represent the lateral angles (Bennett movement). The points RC and RC represent the geometrical centers from which concentric arcs AA and BB may be struck to represent the direction of side bite movements of the teeth. Thus RC and RC are the rotation points of a mandible having the Gothic arch angles of 60 degrees (each side), and lateral Bennett angles of 20 degrees (each side), out of which all horizontal movement comes. Lines MG and QG' locate the buccal surfaces of the upper teeth.

If several points lingual to and more or less parallel to lines MG and QG' corresponding to the several elevations and depressions of the lower teeth be located, and, using points RC and RC as centers, concentric arcs of circles be drawn through these points corresponding to lines AA and BB, they will together with lines DD drawn through these several points and parallel to the sagittal plane SI, outline in a definite way the occlusal surfaces of the lower posterior teeth.

The upper teeth are developed from the same

geometrical figure with the cusps placed distally one half cusp with reference to the lower teeth and buccally according to the lines MG and QG', and are, in common with the lower teeth developed from concentric arcs from the same rotation centers, therefore the primary cusp planes of one jaw necessarily harmonize with the opposing cusp planes of the opposite teeth during jaw movements.

10 Figure 2 shows a schematic side elevation of the machine for cutting the primary forms, any good adaptable articulator will serve in this capacity. The point M represents the right condyle, also shown as M in Figure 1. Point I, also shown in Figure 1, represents the point where the upper central incisor meets the lower central incisor. The plane V is the incisal guide plane fixed to the lower portion of the machine at an angle of 30 degrees from the horizontal plane of occlusion, 20 and by which, the incisal guide pin W is guided in the right and left lateral movements. The dotted circle Y represents the condyle of the machine, which corresponds to the glenoid fossa of the human skull and serves to guide the upper portion 25 of the machine in any predetermined direction relative to the lower portion.

The line XX' represents the condyle inclination which is 30 degrees from the horizontal plane of occlusion, shown as line HH'. The arc CC' represents the arc of a sphere whose radius is 6 $\frac{3}{8}$ inches, the center of which is represented by R, and which, as before described, is obtained by grinding two blocks of plaster together on an articulator with the condyle inclinations set at 30 degrees, thus establishing the lateral and antero-posterior tooth curve.

The method employed to cut our primary tooth forms for the lower right and left posterior teeth, is to fix a block of plaster or artificial stone to the lower portion of the cutting machine, this block to have the equivalent of the concave arc of a 12 $\frac{1}{2}$ inch sphere. This block is fixed in position so that its antero-posterior arc corresponds to arc CC' shown in Figure 2, while its lateral arc corresponds to arc CC' shown in Figure 8.

The cutting tool, shown as 50, Figure 4, is selected according to the angles necessary for any particular cut and attached to the upper portion 50 of the machine in a position so that the point of the cutter, when the machine is in centric position, rests on the block at a point corresponding to a point shown in Figure 1, formed by the intersection of arcs AA and BB.

55 The depth of cut is adjusted, and with the moving parts of the machine M, Q and V, Figure 2, set at angles hereinbefore stated, we cause the upper portion of the machine to make the right lateral motion, corresponding to arcs AA Figure 1, thereby cutting a groove in the plaster, which represents the mesial inclined plane of one cusp and the distal inclined plane of the adjacent cusp. The machine is returned to centric position, another tool selected according to the angulation necessary for the left lateral cut, and left lateral motions made, corresponding to arcs BB, Figure 1. One cut only is made at a time and all cuts are made in lateral direction only. Continuing these cuts from each of the several points, as shown in Figure 1 and points 1A, 2A, 3A, etc., Figure 7, give the primary forms of the occlusal or chewing surfaces of the eight lower teeth. In cutting the primary forms of the upper teeth it is only necessary to reverse the cutting tools to the lower portion of the machine and place a block of

plaster having a convex surface on the upper portion, otherwise the process is substantially the same, except for minor details such as starting points for the cutters and direction of cuts, which, due to the way the cutting machine moves, necessarily are in the exact opposite direction as compared with the lower cuts.

Figure 5 represents the upper, and Figure 7 the lower right side occlusal views of our primary tooth forms after all cuts have been made following the essentials of the geometrical design of Figure 1. A study of the projecting lines will show that Figure 6 is a view of the right side buccal aspect of the upper and lower teeth when they are in occlusion, and further, that the upper teeth are set one half cusp distal to the lower teeth, thus showing how the mesial and distal slopes of the lower cusps approximate the distal and mesial slopes of the upper cusps, and how if the lower teeth are pushed forward in protrusive relation, these planes will slide one upon the other. Then if the lower jaw is moved in lateral or side movement the lower cusp will slide through the grooves provided for them in the upper teeth or upon the inclined planes provided in our teeth for balancing movements. Thus, the plane surface illustrated in Figure 7 extending from the mesial of the first bicuspid distally to the disto-marginal ridge of the first molar as represented by (6A—6A'); (6B—6B'); (1A—1A'); etc., to points 30 (3B—4A'); also the plane surface 4Y', 4A in the distal of the first molar running distally to points (6A—6A') at the distal of the second molar represent the guiding planes for the opposing teeth during mastication or the so-called balancing 35 planes, also shown as line (2A—13A) in Figure 9.

The contact of this plane against the corresponding plane in the upper teeth supports this side of the denture when active chewing is taking place on the other or working side, thus balancing 40 the lower denture against the upper.

The lines AA and BB in Figure 7 represent arcs of concentric circles dropped from the rotation centers shown as RC and RC Figure 1, and which together with lines DD also shown in Figure 1 map out the occlusal surfaces of the teeth.

The points 6A, 1A, 2A, 3A, etc., in Figure 7 represents the points where the cutting tools start their cuts for the lingual cusp cuts and the balancing plane cuts, and points such as MM 50 for the buccal cusp cuts in the lower jaw. Likewise points 6B, 1B, 2B, etc., Figure 5, for the balancing plane cuts and buccal cusp cuts and points as NN for the lingual cusp cuts for the upper jaw. All points are further shown and 55 designated by the same figures in the buccal view shown in Figure 6.

Figures 5 and 7 illustrate the formation of the buccal and lingual cusp planes at different levels. The transverse planes in all teeth are cut on 60 concentric arcs from the rotation centers, the buccal and their contiguous lingual cusp planes are cut on the same arc from one rotation center, but are interrupted vertically by the balancing plane which has its origin in the other rotation center.

In Figure 9 the lines 3H—2A and 13A—MM represent the lingual and buccal cusp planes which are cut on the same concentric arc (AA Figure 1) from the occlusal aspect, but which, 70 as shown by Figure 9 from the transverse vertical aspect, are cut at different levels to conform to the lateral curve of the arc of a 12 $\frac{1}{2}$ inch sphere, and which are separated by the balancing plane 2A—13A. This vertical separation is also 75

illustrated in Figure 10 which shows a perspective view of the buccal and lingual cusps (separated by the balancing plane XY—XY, therefore forming depressions, ridges and corners which act as cutting edges, and planes which act as guiding planes for opposing tooth planes during lateral, protrusive and retrusive bite movements.

The junction of the mesial and distal planes of a lower buccal cusp with the balancing plane, Figure 1, forms a trihedral angle corner in positive relief, with the three faces 4, 5 and 6 meeting at point 5B, also shown as 5B, Figure 7. The counterpart of this positive corner in the opposing upper tooth, is shown by planes 1, 8 and 9, Figure 5, meeting together at point 5B to form a negative trihedral corner. The positive trihedral corner of the lower tooth fits exactly into and is complementary to the negative trihedral angle corner in the upper tooth when the upper and lower teeth are articulated.

The junction of the balancing plane XY, XY, Figure 10 with the mesial and distal lingual cusp planes at point 5A forms a trihedral angle corner in negative relief, with the three faces 1, 2 and 3 meeting at point 5A, also shown as point 5A, Figure 7.

The complementary positive corner in the opposing upper tooth is shown in Figure 5 the three faces of the trihedral angle meeting at point 5A. In this manner all positive and negative trihedral angle corners of the lower teeth fit into their complementary negative and positive trihedral angle corners of the upper teeth. The points of the negative trihedral angle corners in the lower jaw are shown in Figure 7 as 1A, 2A, 3A, 4A and 5A, and the positive corners as 0B, 1B, 2B, 3B, 4B and 5B; for the upper jaw the negative trihedral angle corners are 1B, 2B, 3B, 4B and 5B, Figure 5, and the positive corners are 1A, 2A, 3A, 4A, 5A and 6A.

Referring to the geometrical design of the transverse occlusal cusp angles of our teeth Figure 1, the angles formed by the inter-sections of the arcs AA and BB with the lines DD, progressively become less from the mesial of the first bicuspid to the distal of the second molar, the progressive difference being greater in the angles between arcs BB and lines DD than the angles between the arcs AA and lines DD. As before mentioned the arcs AA, BB and lines DD map out the occlusal surfaces of our teeth, the arcs BB outlining the balancing planes of the teeth, and the arcs AA, the buccal and lingual cusps. Since the primary cusps following these arcs develop the cusp planes and corners of the teeth and all cusps follow the arcs AA and BB, the angles of the faces of the trihedral angle corners made by the intersections of these cuts vary progressively from the first bicuspid to the second molar, therefore no two trihedral angle corners, either positive or negative, upper or lower, have the same combination of angles. All face angles (lower disto-lingual) such as 2, Figure 10, and 9 (upper mesio-buccal) Figure 5, in the negative trihedral angles, together with all face angles such as 6 (lower mesio-buccal) Figure 10, and 11 (upper disto-lingual) Figure 5, in the positive trihedral angles, become progressively less from the first bicuspid to the second molar. The other two face angles of each trihedral angle, such as faces 1 and 3, Figure 10, and 7 and 8, Figure 5 in the negative corners, and the faces 4 and 5, Figure 10, and 10 and 12, Figure 5, in the positive trihedral corners, become progressively greater from first bicuspid to sec-

ond molar. Therefore no two faces of any single trihedral angle either positive or negative, upper or lower, have the same angle.

Referring to Figure 9, the angle 3H, 2A, 13A formed by the lingual cusp plane 3H—2A, and the balancing plane 2A, 13A, form what is known as the tooth openings for the lower tooth, and the angle 2A, 13B—MM the tooth opening angles for the upper teeth. The importance tooth opening angles play in securing the best balance between cutting and grinding ability and denture stability is illustrated in Figure 8, which shows a sectional view at the first molar region after these teeth have been made into upper and lower dentures. U represents the upper denture and W the lower denture. CC' shows the lateral curve corresponding to CC', Figure 2, and HH' the horizontal plane of occlusion corresponding to HH', Figure 2; R the center from which CC' the arc of a 12 $\frac{1}{2}$ inch sphere was struck, also shown as R, Figure 2. CD and AB are sectional views of upper and lower right first molars, through point 3A, Figure 6, with the vertical lingual cusp angle shown at 16 degrees, and the vertical balancing plane angle at 32 degrees from the horizontal plane of occlusion.

The vertical forces of mastication when applied as in chewing food between the balancing planes, represented by line ee', the lateral force developed is in the direction of the arrow f, thereby becoming a retention force. When food is caught between planes marked j and n, the direction of the lateral force is indicated by the arrows g and h, both of which fall within the border of the denture and are retention forces. When equal pressure is brought to bear on planes ee' and j and n, the resulting force is in a vertical direction or parallel to the long axis of the tooth, thereby becoming a retention force.

Acute cusp angles, while being efficient in cutting food, develop less friction, permit slippage, and develop strong displacement forces. Obtuse cusp angles develop a large increase in friction, a lesser ability to cut food, and require greater force to masticate, thereby creating a tendency to dislodge the dentures and an eventual injury to the soft tissues under the denture from overuse. Thus it is apparent that there is a balance in angulation of posterior teeth which gives the proper stability of the denture with a maximum of cutting and grinding ability. Our invention embodies all of these qualities to a common maximum, and since the composite angles from the horizontal aspect at which our teeth are cut are beyond the large majority of human mandibular movements, and our cusp planes are all cut on concentric arcs from the rotation centers, we therefore have all lower cusp planes parallel in all relations to the opposing upper cusp planes during masticating movements, it follows then, that there can be no interference between these parallel planes in either lateral, protrusive or retrusive movements of the mandible.

We have now described our new and improved method of cutting our original tooth forms, which, with the exception of the advantages derived from our special system of cusp plane relief for treating these or other primary forms, embody all of the necessary mechanical requirements of the perfect denture.

As hereinbefore mentioned 85 per cent of protrusive condyle inclinations are between 25 and 35 degrees with the average of 30 degrees. All prosthetic operators use some method to transfer

the trial bite rims from the mouth to the articulator. Operators register condyle movements in various ways, some more exactly than others. In all cases there is the factor of human error.

5 Again when the teeth are articulated in the denture there may be error, and in vulcanizing there may be movement of the teeth. Correction of these errors may or may not be attempted later by grinding, in any event, the correction 10 is at the expense of the original form and efficiency of the teeth.

It is evident that if a method could be devised to change the angle of or relieve the protrusive balancing cusp planes of the primary tooth form 15 so as to create a 10 degree range in condyle inclinations with the center of the range at the 30 degree average without losing protrusive cusp contact with any combination of protrusive angles within this range, 85 percent of human protrusive jaw angle combinations could be fitted from the average 30 degree setup without altering the teeth by grinding. From the transverse standpoint such a method should change all necessary planes to eliminate lateral interference. 20 This method should further provide relief between the opposing balancing planes to allow a slight freedom in centric or rest position. It should slightly widen all necessary sulci and relieve all necessary tooth planes and marginal 25 ridges to allow free movement of opposing cusps even when teeth are somewhat twisted or malposed, due to faulty technic in the setup or movement of the teeth during the vulcanizing process. The method should be such that these 30 reliefs and clearances are all machine cut with the same degree of accuracy found in the primary forms, and, while doing this, not alter the fundamental character of the primary forms.

The final object of our invention is to incorporate these new and novel features in our tooth forms. We have developed a cusp plane relief system to provide lateral, retrusive and internal intercusp plane clearance, thereby changing the character of the primary forms from cusp plane 45 contacts to point contacts with the opposing teeth, as shown by points 3N and 4N, Figure 9.

Figure 6 shows a schematic side elevation of the upper and lower right eight teeth. The line 3A, 4X represents a normal first molar 30 degree cusp plane, the angle 3X, 3A, 3X' shows the amount of cusp plane relief between opposing teeth necessary to relieve binding or interference of cusps and maintain protrusive balancing contact when condyle inclinations are changed 50 from 30 degrees to a greater or less degree. The line 3B—4T Figure 6 represents the normal distal or retrusive facet angle, the angle 3T—3B—3T' shows the amount of relief necessary to relieve interference and maintain balance when the condyle inclinations are lessened, and again, the angle 3Z, 3A, 3Z', also a retrusive facet angle, shows the amount of clearance necessary to maintain protrusive balance when the condyle 55 inclinations are increased. It is to be understood that this clearance is taken equally from the upper cusp planes as well as the lower cusp planes as illustrated in Figure 6. The amount of clearance as specifically shown is approximately five degrees. This schematic view also shows how the plane contacts are altered to become point contacts, the points of contact being 1A, 2A, 3A, 3A, 5A.

The method employed to produce these lateral, protrusive, retrusive and internal clearances, is 60 to start with the completed model in which the

full number of primary planes of the full set of posteriors have been cut. The clearance angles for the various cutters having been determined according to the angles shown in Figures 6 and 9, and incorporated in the cutting tools, the cuts 5 are made by seating the tools exactly in the previous cuts, and, varying the directions in which the knives cut, and using lateral cutting movements only, make all necessary cuts. It is to be understood that this clearance or relief 10 system can be used equally as well on primary forms cut by any other method as well as on primary forms cut by our method.

Figure 7 shows the occlusal view of the lower right posterior teeth which may be used as an 15 example for the method of cutting either upper or lower clearances. The 0A, 1A, 2A, 3A, etc., to point 6A are the points where each corresponding cutter is seated to start the lateral clearance cut in the lingual cusps. The change in the direction of the cuts is illustrated by the arrows 3A, QQ and 3A, Q'Q', and the direction of the 20 cuts are in lingual direction. The cuts for the buccal cusp clearances are also in lingual direction, starting at points as MM, and cutting in 25 the directions as shown by the arrows MM—2D and MM—2D', to and over the crest of the upper edge of the balancing plane in the inter-proximal space between the second bicuspid and first 30 molars.

The lateral view of the change in cusp plane angles when these lateral cuts are made is shown in Figure 6. It becomes apparent that the angles of the cutters themselves have been changed in addition to the change in lateral direction of 35 cuts. Thus in Figure 6, the line 3A—4X, starting from the central fossa of the lower first molar, and extending up and back to intersect the line 4T, 3B, to form the crest of the disto-buccal cusp of the first molar, forms an angle of 30 degrees 40 from the horizontal plane of occlusion. This same angle is found in all similar angles in our teeth when they are cut at our 30 degree angle. However, when the clearance system is used, it becomes necessary to sharpen the cutters at the 45 new clearance angles before they are used. Figure 6 shows these clearances, thus line 3A, 4X, in the first molar, is the 30 degree angle, line 3A, 3X, the mesial clearance angle of the disto-buccal cusp of the lower first molar, and the line 3A, 3X' 50 is the clearance angle of the distal slope of the mesial buccal cusp of the upper first molar. This clearly shows the angle of clearance 3X, 3A, 3X', which as before mentioned is taken from both upper and lower cusp planes. All other clearances 55 are obtained in the same manner, so it follows that the protrusive, retrusive and lateral clearances are all cut by the same cutters at the same time. Further than this, as evidenced by Figure 9, the change in lateral direction of the cutters while 60 opening up the grooves in lateral direction, also change the vertical angles of the buccal and lingual cusps from the horizontal plane of occlusion. Thus, the change in the angles for both the upper and lower teeth would be the angles as represented by 3H, 2A, 3H', for the lingual cusps, and 65 13A—MM, 2A', for the buccal cusps, and either the upper or lower clearance alone would be one half of this angle.

The internal clearance of the teeth is represented by the change in the angles of the balancing planes, shown as XY, XY, Figure 10, also shown as lines 2A, 13A, in Figure 9, and also represented by the vertical clearance in the buccal and lingual cusp planes made by the lateral 75

clearance cutters. The method to secure the balancing plane clearance is to incorporate the proper angles in the cutting tools, and, as illustrated on the lower jaw Figure 7, starting at the inter-
5 proximal space between the two bicuspids point 5
2A, the direction of the cut is changed from 2A,
2B', and 2A', 2B, to the directions of the arrows
2A, 9T, and 2A', 9T', thus changing the angle of
the balancing plane of the mesial cusp of the first
10 molar. This method is used on all balancing
planes on both upper and lower posteriors, thus
producing a clearance as shown in Figure 9.

The angle 23', 2A, 23 represents the angle of
15 clearance that is cut off the lower balancing
plane. The angle 24', 13B, 24 represents the
angle cut off the upper balancing plane. Thus
the clearance between these two balancing planes
becomes rectangular in appearance.

Our clearance system is therefore a series of
20 lateral cuts for the buccal cusps of all teeth, a
similar series for the lingual cusps, and another
series for the balancing planes. The buccal and
lingual cuts produce lateral clearance, protrusive
and retrusive clearance, and also part of the in-
25 ternal clearance. These lateral cuts together
with the cuts for the balancing planes produce
complete relief and change posterior teeth from
plane contacts to point contacts. The relief
30 angles of teeth treated by this method are neces-
sarily small and do not change the character of
the form sufficiently to alter the compensating
or lateral curves which, as hereinbefore stated,
are the arcs of a 12½ inch sphere. The relief
35 angles are sufficiently great to relieve or alter all
necessary surfaces so that they will have the
necessary clearance to balance, without change of
curve or setup in the denture, in protrusive and
retrusive relation as much as 5 degrees above and
40 5 degrees below the angle at which they were
cut, or any bilateral combination of angles within
in this range. The relief angles also provide a
sufficient lateral clearance to effectively eliminate
cusp interference in lateral jaw movements and
45 produce freedom from cusp locking in centric
relation. The system further produces sufficient
clearance to compensate to a large extent for
movement of teeth during vulcanization and dis-
crepancies in the setup.

Figure 11 illustrates one of our teeth after it
50 has been separated from its adjacent teeth in
the block, the excess plaster carved away, and
the anatomical features of a natural tooth in-
corporated, without destroying the primary cusp
planes, thereby bringing the primary forms with
55 their precision cut planes and cusps up to the final
perfected stage when they may be used as models
from which artificial teeth may be manufac-
tured. The grooves marked 20 have been carved
into the mesial and distal marginal ridges in all
60 teeth so as to form a series of landmarks, which,
if placed in alignment in adjacent teeth, will au-
tomatically place the teeth in dentures in their
correct position both with relation to their op-
posing as well as their adjacent teeth.

65 We have now described our new and improved
method of cutting our primary forms together
with our method of creating lateral, protrusive,
retrusive and internal cusp plane relief in these
forms. Our method is not restricted or confined
70 to the thirty degree teeth using as a basis the
segment of a 12½ inch sphere, this, in our op-
inion, produces the most efficient and best ana-
tomatic teeth, but the method can be used with
75 equal facility to produce teeth using, as a basis,
segments from any sized sphere. Our system

of cusp plane relief is not confined to our 30 de-
gree teeth, or even to our method of cutting pri-
mary forms, and can be used with equal facility
on any degree teeth cut by our method or any
other method.

Summary

Briefly summarized, our improved model form
for artificial posterior teeth is one in which all of
the cusps are of trihedral form with transverse
grooves therebetween having the buccal and
lingual portions in alignment and the apices of all
cusps lying in the surface of a sphere. A further
feature of the construction is that two of the
faces of each cusp of teeth on one side of the
jaw are generated by a transverse movement from
a center on the same side of the jaw while the
third face of the cusp is generated by a move-
ment from a common center on the opposite side
15 of the jaw. Thus with such a form all of the
opposed cusps in the upper and lower teeth re-
main in contact with each other during either
transverse or protrusive movements of the lower
jaw, and without interference to such movements.

A further feature of our model is that the
opposed faces of the cusps in the upper and lower
jaw are at slightly divergent angles so as to pro-
vide freedom for jaw movement.

What we claim as our invention is:

1. A model form for a series of artificial pos-
terior teeth comprising buccal and lingual tri-
hedral cusps having aligned transverse ridges and
grooves therebetween with the buccal and lingual
portions of each transverse groove in alignment
in each of the teeth.

2. A model form for a series of artificial pos-
terior teeth comprising buccal and lingual tri-
hedral cusps having aligned transverse ridges and
transverse grooves therebetween with the buccal
and lingual portion of each groove in alignment,
two of the faces of each trihedral cusp being gen-
erated by a transverse movement from a common
center on the same side of the jaw and the third
face being generated by a transverse movement
from a common center on the opposite side of the
jaw.

3. A model form for a series of artificial pos-
terior teeth comprising buccal and lingual tri-
hedral cusps having aligned transverse ridges and
transverse grooves therebetween with the buccal
and lingual portion of each groove in alignment,
two of the faces of each trihedral cusp being gen-
erated by a transverse movement from a common
center on the same side of the jaw and the third
face being generated by a transverse movement
from a common center on the opposite side of the
jaw, the center for generating the two faces on
one side of the jaw being the same as that for
generating the third face on the opposite side
of the jaw.

4. A model form for a series of artificial pos-
terior teeth comprising buccal and lingual tri-
hedral cusps having aligned transverse ridges and
transverse grooves therebetween with the buccal
and lingual portion of each groove in alignment,
two of the faces of each cusp being generated by
a transverse movement from a common center on
the same side of the jaw, of lines at an obtuse
angle to each other in a plane passing through
said center and the third side of each cusp being
generated by a transverse movement of a line
moving from a common center on the opposite
side of the jaw, the center of movement of the
third side of the trihedral angles on one side of
the jaw being the same as the center of movement

for two sides of the trihedral angles on the opposite side of the jaw.

5. A model form for a series of artificial posterior teeth comprising upper and lower teeth on opposite sides of the jaw all provided with buccal and lingual trihedral cusps having aligned transverse ridges and transverse grooves therebetween with the buccal and lingual portions of each groove in alignment, the apices of all of said 10 cusps being relatively positioned to lie in the surface of a sphere and the faces of the cusps being in such angular relation that two of said faces of each cusp on one side of the jaw are generated by a transverse movement from a common center on 15 the same side of the jaw, and a third side of each cusp being generated by a transverse movement from a common center on the opposite side of the jaw and all of said cusps of the teeth on the upper and lower jaws remaining in contact in all 20 positions of transverse movement.

6. A model form for a series of artificial posterior teeth in which all bicuspids have only positive trihedral angles formed by the abutting of three inclined planes, two of which run buccolingually and being generated from a common center on the same side of the jaw and the third running mesio-distally and being generated from a common center on the opposite side of the jaw.

7. The method of generating model forms for 30 artificial posterior teeth which consists in moving in engagement with a cuttable blank cusp cutters for teeth on one side of the jaw transversely from a common center on the same side of the jaw to form two faces of each trihedral cusp 35 and for moving the cutter for the third face of the cusps transversely from a common center on the opposite side of the jaw whereby all faces of all of the cusps are generated by transverse movements from only two centers.

40 8. A model form for a series of artificial posterior teeth comprising upper and lower teeth on opposite sides of the jaw, all provided with trihedral cusps and transverse grooves therebetween with the buccal and lingual portions of each groove in alignment, the apices of all of said cusps being relatively positioned to lie in the surface of a sphere and the faces of the cusps being in such angular relation that two of said faces of each cusp on one side of the jaw are 45 generated by a transverse movement from a common center on the same side of the jaw and a third face of each cusp being generated by a transverse movement from a common center on the opposite side of the jaw, all of said cusps of the teeth on the upper and lower jaws remaining in contact in all positions of transverse movement and the angles of the opposed cusps on the upper and lower jaws being slightly divergent to provide freedom for jaw movement.

50 9. A model form for a series of artificial posterior teeth comprising opposed upper and lower teeth on both sides of the jaw, all provided with positive trihedral cusps and negative trihedral recesses therebetween, all the positive trihedral 55 angles of the cusps simultaneously engaging the corresponding negative trihedral recesses on the opposed teeth and the positive trihedral angle being slightly less than the negative trihedral angle not to exceed a maximum of approximately five

degrees to provide freedom of jaw movement in directions forward and rear and laterally.

10. Model forms for opposed upper and lower artificial teeth including bicuspid teeth and molars, each of said bicuspid teeth comprising only two positive trihedral cusps, with transverse grooves between adjacent teeth having the buccal and lingual portion of each groove in alignment, said positive trihedral cusps being separated by a balancing plane to form one positive trihedral buccal cusp, and one positive trihedral lingual cusp so positioned relatively to the molars, that the apices of each lingual cusp wholly occupy the interproximal space between the two opposing teeth.

15 11. Model forms for artificial molar teeth comprising trihedral cusps with transverse grooves therebetween and with buccal and lingual portions of each groove in alignment, having facets on their masticatory area formed of a plurality of surfaces arranged in inclined planes, said planes coming together at angles constituting trihedral cusps, said cusps being arranged in pairs bucco-lingually and having substantially the same alignment as the transverse grooves, and further, all facet surfaces extending in a transverse direction being interrupted by a balancing plane and divided thereby into buccal and lingual portions.

20 12. Model forms for artificial posterior teeth, having blended into the occlusal anatomical surfaces, small grooves carved in the center of the mesial and distal marginal ridges of all teeth, so positioned that when the teeth are assembled they serve as land-marks, which are in alignment 25 in adjacent teeth, when set correctly.

25 13. Model forms for upper and lower posterior teeth comprising buccal and lingual trihedral cusps having aligned transverse ridges and aligned transverse grooves therebetween with the buccal and lingual portions of each groove in alignment, no two trihedral angles in said 30 models either upper or lower positive or negative having the same angulation or combination of angles.

35 14. The method of generating model forms for artificial posterior teeth which consists in moving in engagement with a cuttable cusp cutters for teeth on one side of the jaw transversely from a common center on the same side of the 40 jaw to form two faces of each trihedral cusp and moving the cutters for the third face of the cusp transversely from a common center on the opposite side of the jaw whereby all faces of all the cusps are generated by transverse movements 45 from only two centers, forming opposed teeth which match with said generated teeth without clearance therebetween, and in refashioning said teeth by moving a new set of cusp cutters in engagement with the cuspal surfaces of said 50 teeth from the aforesaid two centers only and in a transverse direction only, said new set of cusp cutters having the angles incorporated in them that would be required of cusp cutters to cut teeth at an angle of five degrees greater and five degrees less than the primary model forms thereby increasing the functional range.
